UNITED STATES PATENT OFFICE.

ELIJAH CHETWYND, OF HANLEY, STAFFORDSHIRE, ENGLAND, ASSIGNOR
TO BIRKS BROTHERS & SEDDON, OF SAME PLACE.

DESIGN FOR TABLE-SERVICE.

Specification forming part of Design No. 11,517, dated November 18, 1879; application filed October 25, 1879.
[Term of patent 7 years.]

To all whom it may concern:

Be it known that I, ELIJAH CHETWYND, residing at Hanley, Staffordshire, England, have originated and designed a new, useful, and ornamental Design for a Table-Service, of which the following is a full, clear, and exact description, reference being had to the accompanying photographic illustration, making part of this specification.

The essential feature of my design consists, as here shown, of a raised or "struck-up" portion representing a hop-vine entwining a hop-pole with hops falling in the center. It may be applied to various articles of domestic use, but is specially adapted for those articles usually included in a table-service.

In the photographic illustration of my design is shown only a pitcher, vegetable-dish, and cover, and these are plain in their general outline, but contain the essential feature of my design, showing it in this instance as follows: The handles of the articles are made to imitate a hop-pole entwined by a hop-vine, the falling hops being shown on the body of the article.

In the photographic illustration, A designates the pitcher; B, the vegetable-dish, and C the cover. a designates the representation of a hop-pole; b, the vine, and c the falling hops.

I claim as my invention—

1. A design for table-service and other domestic articles, consisting of a representation of a hop-vine entwining a hop-pole, with hops falling in the center, substantially as above described.

2. A design for table-service and other domestic articles, in which the handles are made to represent a hop-vine entwining a hop-pole, substantially as above described.

In testimony that I claim the above-described design for a table-service, I have hereunto set my hand this 8th day of May, A. D. 1879.

ELIJAH CHETWYND.
